The ornamental design for a raised garden bed, as shown and described.

DESCRIPTION

FIG. 1 is a front perspective view of a raised garden bed in accordance with a first embodiment of my new design, with an opening therethrough defined by the sides of the raised garden bed, and with a rear perspective view being identical thereto;

FIG. 2 is a left side perspective view of the raised garden bed as shown in FIG. 1, with a right side perspective view being identical thereto;

FIG. 3 is a top view of the raised garden bed as shown in FIG. 1, the bottom view of which is an identical view thereto;

FIG. 4 is a front view of the raised garden bed as shown in FIG. 1, the rear view of which is an identical view thereto; FIG. 5 is a left side view of the raised garden bed as shown in FIG. 1, the right side view of which is an identical view thereto;

FIG. 6 is a perspective view of the raised garden bed as shown in FIG. 1, with another similar raised garden bed adjacent thereto in a first configuration shown in broken line; and FIG. 7 is a perspective view of the raised garden bed as shown in FIG. 1, with another similar raised garden bed adjacent thereto in a second configuration shown in broken line.

FIG. 8 is a front perspective view of a raised garden bed in accordance with a second embodiment of my new design, with an opening therethrough defined by the sides of the raised garden bed, and with a rear perspective view being identical thereto;

FIG. 9 is a left side perspective view of the raised garden bed as shown in FIG. 8, with a right side perspective view being identical thereto;

FIG. 10 is a top view of the raised garden bed as shown in FIG. 8, the bottom view of which is an identical view thereto;

FIG. 11 is a front view of the raised garden bed as shown in FIG. 8, the rear view of which is an identical view thereto;

FIG. 12 is a left side view of the raised garden bed as shown in FIG. 8, the right side view of which is an identical view thereto;

FIG. 13 is a perspective view of the raised garden bed as shown in FIG. 8, with another similar raised garden bed adjacent thereto in a first configuration shown in broken line; and

FIG. 14 is a perspective view of the raised garden bed as shown in FIG. 8, with another similar raised garden bed adjacent thereto in a second configuration shown in broken line.

FIG. 15 is a front perspective view of a raised garden bed in accordance with a third embodiment of my new design, with an opening therethrough defined by the sides of the raised garden bed, and with a rear perspective view being identical thereto;

FIG. 16 is a left side perspective view of the raised garden bed as shown in FIG. 15, with a right side perspective view being identical thereto;

FIG. 17 is a top view of the raised garden bed as shown in FIG. 15, the bottom view of which is an identical view thereto;

FIG. 18 is a front view of the raised garden bed as shown in FIG. 15, the rear view of which is an identical view thereto;

FIG. 19 is a left side view of the raised garden bed as shown in FIG. 15, the right side view of which is an identical view thereto;

FIG. 20 is a perspective view of the raised garden bed as shown in FIG. 15, with another similar raised garden bed adjacent thereto in a first configuration shown in broken line; and,

FIG. 21 is a perspective view of the raised garden bed as shown in FIG. 15, with another similar raised garden bed adjacent thereto in a second configuration shown in broken line.

Any broken line illustration of environmental structure in the drawings and selected other features that may be shown as attached to the claimed design are for illustrative purpose only and form no part of the design. The raised garden bed is shown in FIGS. 8-14 with a symbolic break in its length. The appearance of any portion of the article between the break lines forms no part of the claimed design.
